UNITED STATES PATENT OFFICE.

CARL A. KARELIUS, OF PASADENA, CALIFORNIA.

CORNER-BEAD-POSITIONING DEVICE.

Application filed June 12, 1926. Serial No. 115,565.

My invention relates to corner bead positioning devices of the character embodied in my co-pending application Serial No. 95,354, filed March 17, 1926.

5 It is a purpose of my present invention to provide a corner bead positioning device by which the corner beads of single or double side pilasters can, with facility and dispatch, be properly positioned both vertically and 10 horizontally and maintained in proper position until the plastering operation has been completed.

I will describe only two forms of corner bead positioning devices embodying my invention, and will then point out the novel 15 features thereof in claims.

In the drawings

Figure 1 is a view showing in side elevation one form of corner bead positioning 20 device embodying my invention in applied position to a pair of corner beads;

Figure 2 is a view showing in plan section a pilaster having applied thereto the positioning device shown in Figure 1;

25 Figures 3 and 4 are sectional views taken on the lines 3—3 and 4—4 of Figure 2;

Figure 5 is a sectional view taken on the line 5—5 of Figure 1;

Figure 6 is a view similar to Figure 2, 30 showing a modified form of my invention in applied position to a single side pilaster.

Similar reference characters refer to similar parts in each of the several views.

Referring specifically to the drawings, and 35 particularly to Figure 1, my invention in its present embodiment comprises a pair of units, and as the construction of the two units is identical a description of one will suffice for both. As shown in Figure 2, each 40 unit comprises a pair of frames F and F' formed of metal or other suitable material and both of L-shaped form. The frame F is provided with a short arm 15 carrying a clamping screw 16, and a long arm 17 carrying a set screw 18. The arm 15 is constructed 45 from a channel bar which may be formed integral with or welded to the arm 17, while the latter has the cross sectional contour shown in Figure 3. The frame F' comprises a relatively short arm 19 of the same 50 construction as the arm 15 and provided with a clamping screw 20. The frame F' also includes a long arm 21 in the form of a channel bar of such dimensions as to be slidably received within the arm 17 of the frame F and through the medium of the set screw

18 the arm 21 is capable of being locked in any longitudinally adjusted position within the arm 17 so as to vary the parallel relation of the arm 19 with respect to the arm 15. 60

The arms 15 and 17 have slideable thereon brackets 22 and 23, respectively, capable of being locked in any adjusted position by means of screws 24 and 25, respectively. These brackets co-operate with the arms in providing a clamp for securing a corner bead B to the frame in the manner shown in Figure 2. By virtue of the fact that they are adjustable, it will be understood that the brackets are capable of clamping the various sizes of corner beads. The frame F' is provided with a similar bracket 26 adjustable on the arm 19 and capable of being locked in adjusted position by a screw 27. 70 This bracket 26 is adapted to co-operate with a bracket 28 which, as shown in Figure 5, is disposed within the arm 21 and is slotted to receive a screw 29 by which the bracket can be locked in longitudinally adjusted position on the arm. The head of the bracket 28 is recessed as shown in Figure 5, in order to provide a surface 30 which is flush with the inner side of the arm 17 so that when a corner bead B' is clamped between the brackets 28 and 26 as shown in Figure 5, it 80 will occupy the same relative position as the bracket B in the frame F. 85

In practice, the two units are associated with a pair of corner beads B and B' in the manner illustrated in Figure 1, the beads being securely clamped by means of the brackets 22 and 23, etc., thus serving to maintain the units in spaced relation. The device is now ready to be applied to a double face pilaster in the manner shown in Figure 2, with the clamping screws 16 and 20 disposed to engage the sides of the pilaster and when screwed into clamping engagement with the pilaster to secure the two units in horizontal position, one above the other, and to thus properly position the corner beads with respect to the corners of the pilaster. Various methods of positioning the two units to effect the proper supporting of the corner beads may be employed. By first determining the points at which the clamping screws 16 and 20 of the upper units are to engage the sides of the pilaster, through the use of a plumb bob, the points at which the clamping screws of the lower unit engage the sides of the pilaster can be readily determined, thus positioning the two 100 105 110

units so that the corner beads will occupy perpendicular positions at the corners of the pilaster.

When once clamped to the pilaster the two units serve to rigidly support the corner beads in proper position at the corners of the pilaster so that the plaster can be applied in the usual manner on the corner beads, and thus be properly positioned within the plaster.

It will be understood that the two units are capable of adjustment to accommodate the device to pilasters of different sizes, and as the corner bead brackets are likewise capable of adjustment to accommodate different size beads, it will be manifest that the device in its entirety is capable of universal use in its adaptation to various sizes of pilasters and the holding of corner beads in various spaced positions with respect to the corners of the pilaster.

Referring now to Figure 6, I have here shown a modification of the device, in which the frames F of each of the units only is employed, and in conjunction with a frame F² having a long arm 31 slidable in the arm 17 and capable of being locked in any adjusted position by the screw 18, and a short arm 32 adapted to engage a strip of plaster of Paris 33 which may be applied to the front of a single side pilaster as shown in Figure 6. The flat side of the strip 33 is made perpendicular so as to form an abutment against which the short arm 32 of each frame F² depends, and with the two units embracing a corner bead B² as shown in Figure 6, it will be clear that the two units co-operate in supporting the corner bead in perpendicular position with respect to the corner of the pilaster and to securely hold the same in applied position while the plaster is being applied.

Although I have herein shown and described only two forms of corner bead positioning devices embodying my invention, it is to be understood that various changes and modifications may be made therein without departing from the spirit of the invention, and the scope and spirit of the appended claims.

I claim:

1. A device for positioning corner beads with respect to pilasters comprising means adjustable to clamp a pilaster so as to be supported thereon, and means adjustable to clamp a corner bead on the first means in a manner to properly position the corner bead with respect to the corner of the pilaster.

2. A device for positioning corner beads with respect to pilasters as embodied in claim 1, wherein the first means includes two clamping screws, and the second means two pairs of adjustable clamping brackets mounted for movement on the first means.

3. A device for positioning corner beads

with respect to pilasters comprising a pair of L-shaped frames extensibly connected in the form of a U, clamping screws carried by the parallel portions of the frames, and corner bead engaging brackets arranged in pairs on the frames and coacting to clamp corner beads to the frame.

4. A device as embodied in claim 3, wherein in one of the brackets of one pair is provided with a shouldered surface alined with respect to the inner surface of one arm of the other frame for the purpose described.

5. A device for positioning corner beads with respect to pilasters comprising a pair of frames extensibly associated with each other and having laterally projecting portions between which a pilaster is adapted to be received, means on said portions by which the frames are adapted to be clamped to the pilaster, and means on the frames for supporting corner beads on the frames in proper position with respect to corners of the pilaster.

6. A device for positioning corner beads with respect to pilasters comprising means contractible to engage a pilaster, means for clamping the first means to the pilaster so that the first means will be supported in elevated position on the pilaster, and means on the first means for holding a corner bead thereon to properly position the latter with respect to a corner of the pilaster.

7. A device for positioning corner beads with respect to pilasters as embodied in claim 5 wherein the last means comprises brackets arranged in pairs and slidable on the frames for engagement with the corner beads, and means by which the brackets are adapted to be secured to the frame in clamping relation to the corner beads.

8. A device for positioning corner beads with respect to pilasters comprising a pair of substantially L-shaped frames telescopically associated with each other in the form of a U, clamping screws carried by the parallel portions of the frames, corner bead engaging brackets slidable on the frames, said brackets arranged in pairs with the brackets of each pair co-acting to clamp corner beads therebetween, and means for securing the brackets to the frames in clamping relation to the corner beads.

9. A device for positioning corner beads with respect to pilasters comprising means adjustable to engage and support itself on the pilaster, means for clamping a corner bead to the first means and comprising brackets movably mounted on the first means and between which the corner bead is adapted to be interposed, and means for securing the brackets against movement in clamping relation to the corner bead so as to support the latter in proper position with respect to a corner of the pilaster.

CARL A. KARELIUS.
